UNITED STATES PATENT OFFICE.

HORATIO S. SCOTT, OF ASHLAND, OHIO.

FEED-REGULATOR FOR MIXERS.

1,124,338.

Specification of Letters Patent.

Patented Jan. 12, 1915.

Application filed March 28, 1913. Serial No. 757,377.

To all whom it may concern:

Be it known that I, HORATIO S. SCOTT, citizen of the United States, residing at Ashland, in the county of Ashland and State of Ohio, have invented certain new and useful Improvements in Feed-Regulators for Mixers, of which the following is a specification.

This invention relates to improvements in mixers, and the improvement comprises a feed regulator for a concrete mixer, substantially as herein shown and described and more particularly pointed out in the claims.

The object of the invention is to provide an endless open carrier adapted to traverse through a hopper and cross transversely over the open top of a receptacle to a drive member, the carrier returning beneath the receptacle after dropping and distributing its load through the carrier itself directly into the receptacle. A cross feed of this kind over the receptacle places the material always in plain sight and all the material brought forward is shaken loose and deposited without loss, and by placing the hopper and carrier at right angles to the receptacle with the receptacle within the circle described by the carrier, a very compact and stable machine is obtained. This arrangement also enables the hopper and carrier to be placed low and near the mixing mechanism and the receptacle is not cut away or its depth decreased in any way. Furthermore, no clogging of the carrier occurs, and separate materials can be fed accurately in definite fixed proportions and in an even, continuous unbroken stream. The hopper is also designed to have an adjustable stroke-off device to coöperate with the carrier in regulating the amount of material fed to the receptacle.

Figure 1 is a plan view of the machine. Fig. 2 is a cross section on a line immediately next to the outer hopper and showing the relation of the feed therefrom to the mixer, and Fig. 3 is a cross section on the other side of the said hopper and next to the cement hopper. Fig. 4 is an end view and cross section of the double hopper and its stroke-off device, and Fig. 5 is a sectional view of one stroke-off device.

As thus shown, the machine is mounted upon a suitable four wheel truck having a main frame F and adapted to be moved from place to place, and carries an engine E at one end to supply the necessary operating

power through suitable shaft and gear connections. Power is transmitted by means of said gears G particularly to the opposite outside shaft s from which the carriers c and c' respectively, are alike operated and which operate in conjunction with the sand and gravel or crushed stone hopper h and the cement hopper h', respectively.

Referring first to the hopper h it will be observed that the said hopper in fact is an entirely outside member as to the body and main portion of the machine and is removably supported upon a bottom f of its own which is pivoted at 4 to be tilted over upon the top of the machine when such change of location becomes necessary, and is otherwise supported upon legs 5 having integral segments 6 at their edge adapted to adjust the said legs within limits to various positions and thus take up the slack in the carrier 2, the roller or rollers 7 or their equivalent being located on a shaft or on bearings at 8 in said legs and serving as the outer support for the endless carrier c. Relatively the legs or supports 5 are short and low as compared with the elevation of the mixing trough m, and this brings the hopper h at its deepest outer portion down to such a level as to render it of easy access for filling by shovel or otherwise, and the outside and separate location of the said hopper contributes very materially to these advantages. The hopper bottom f is supplemented at its upper end by a fixed trough shaped extension f' rigid on the main frame and to which bottom f is hinged at 4 as above described, and said extension discharges directly into the head of the mixer over the side wall thereof and at one side. A sprocket or driving wheel or drum 9 on shaft s supports the said carrier c outside the mixer at its right, Fig. 2, and substantially on a plane with the top thereof, so that the carrier passes idly about the mixer from its point of discharge and returns beneath the same to the hopper h, thus crossing entirely over the mixer and down beneath the bottom thereof where it is free to travel back to the hopper. The said carrier c has side links 11 and cross strips 12 affixed thereto which serve to convey the material fed into hopper h forward and upward into the mixer and of course the bottom of said hopper and its extension f' is closed against leakage and the speed of travel of the carrier will mainly determine the amount of material conveyed thereby,

assuming that the hopper is kept supplied with the raw stock and a gate or like control is used. As to this, it is to be observed that the said hopper is divided into two compartments by a wall 14 and one is used to feed the sand and the other the crushed stone or gravel, while the hopper *h'* supplies the cement, as above indicated. An endless carrier *c'* serves for this hopper and passes over and around the mixing trough, as does carrier *c*, and suitable drum or equivalent rollers 15 support the said carrier *c'* at one end and sprocket 16 on shaft *s* on the other Fig. 3.

Suitable gates or shut-offs are employed in and with each hopper to control the feed therefrom by the carriers and said gates, *g* and *g'*, have stroke-offs *n* and *n'* hinged on the lower edges thereof and dominated by springs *o* and *o'* supported on said doors and through ears on the said stroke-offs. Said doors have side wings *w* slideable up and down upon the side plates *t* rigid with the front of the hopper and serving as guides for said wings on pins and slots in said parts. The screws *s'* and *s''* serve to raise and lower said doors and the pressure upon the stroke-offs is applied by the springs *o* and *o'*, respectively, on rods *r* and *r'* respectively, connected with said doors and stroke-offs.

One of the great advantages of the present construction of mixer over others hitherto in use is that it provides a sight feed for all the material that enters the mixer, which enables the operator to see at all times just how the ingredients are coming and that the requisite proportions are being maintained. Once the material is properly fed to the mixer the preliminary work is done and the mixer takes care of the rest. The stroke-offs shown afford accurate measurement of the material according as they may be set for work and refined adjustments thereof are possible by the means shown. Usually I employ a scale with a pointer to fix the feed at a certain point, according to the condition of the material.

What I claim is:

1. In a machine as described, a receptacle, a drive-shaft and wheel thereon at one side of said receptacle, a hopper transversely arranged at the other side of said receptacle opposite said wheel, a bottom for said hopper, a roller at the other end of said recep-

tacle below said bottom, and an endless open carrier extending through said hopper and across the top of said bottom and around said wheel and transversely beneath the bottom of said receptacle to said roller. 60

2. In a machine as described, a receptacle, a drive wheel at one side of said receptacle, a hopper opposite said wheel at the other side of said receptacle having an inclined bottom extending to the side and top of said receptacle, a support for the outer end of said hopper, an idler wheel mounted on said support, and an endless carrier comprising links and cross pieces stretched between and around said wheels through said hopper and transversely across the top of and back beneath the bottom of said receptacle. 65

3. In a machine as described, a receptacle, a sprocket wheel supported at one side of said receptacle, a divided hopper supported transversely at one side of said receptacle opposite said wheel, an inclined bottom for said hopper extending to the side and top of said receptacle, a divided endless carrier extending through said hopper and transversely across said receptacle and around said sprocket wheel and back beneath the bottom of said receptacle, an idler wheel for said carrier supported beneath said hopper bottom at the outer end thereof, and separate adjustable stroke-off devices at the front end of said hopper above said divided carrier. 75

4. In a machine as described, a receptacle, a drive shaft and sprocket wheel at one side of said receptacle, a fixed trough-shaped extension transversely arranged on the other side of said receptacle opposite said wheel, a hopper hinged to said extension, a pivoted support for the other end of said hopper, a carrier wheel mounted on said support, an endless open carrier stretched between said wheels and extending through said hopper and trough-shaped extension and passing transversely over and returning beneath said receptacle, and a stroke-off device above said carrier at the discharge end of said hopper. 90

In testimony whereof I affix my signature in presence of two witnesses.

HORATIO S. SCOTT.

Witnesses:
